DESIGN FOR A COMPACT OR SIMILAR ARTICLE

Harry Morris, Chicago, Ill.

Application May 4, 1944, Serial No. 113,455

Term of patent 14 years

(Cl. D86—10)

To all whom it may concern:

Be it known that I, Harry Morris, a citizen of the United States, residing in Chicago, in the county of Cook and State of Illinois, have invented a new, original, and ornamental Design for a Compact or Similar Article, of which the following is a specification, reference being had to the accompanying drawing, forming part thereof.

Fig. 1 is a top plan view of a compact or similar article in open position showing my design, and

Fig. 2 is a top view of the compact shown in Fig. 1 in closed position, and

Fig. 3 is a side view thereof in open position, and

Fig. 4 is a rear edge view thereof.

The bottom view of the compact is the same as shown in Fig. 2.

I claim:

The ornamental design for a compact or similar article, substantially as shown and described.

HARRY MORRIS.
